CHIN REST FOR VIOLINS

William Halko, Vancouver, British Columbia,
Canada

Application December 8, 1947, Serial No. 790,336

7 Claims. (Cl. 84—279)

1

My invention relates to improvements in chin rests for violins.

The objects of the invention are to provide a rest for a violin which will be adjustable as to height and lateral position; one which will permit the violin to be held in position without strain and which will enable a certain freedom of head and neck movement, which will obviously add considerably to the comfort of the user in avoiding neck stiffness. A further and very important object is to provide a rest which will prevent the damming of tone of the instrument which results from supporting the body of the violin on the fabric of the garment worn by the player. Another object is to provide a support base of substantial area for the shoulder, so that an adequate grip on the instrument is obtained with a modicum of downward pressure on the chin rest.

Referring to the drawings:

Figure 1 is a rear elevational view of the invention with a part in section.

Figure 2 is a transverse sectional view taken on the line 2—2 of Figure 1.

Figure 3 is a sectional view taken on the line 3—3 of Figure 1.

Figure 4 is a plan view.

In the drawings like characters of reference indicate corresponding parts in each figure.

The numeral 1 indicates generally a portion of a violin body to which the invention is to be secured and 2 is the upper and lower marginal beads of said body.

The numeral 4 indicates a clip consisting of upper and lower parts 5 and 6 respectively, each of which is provided with an overhanging lug 7 which is preferably provided with a felt pad 8 to engage the body 1 of the violin. The upper and lower clip parts 5 and 6 are drilled vertically adjacent their side edges to receive a pair of screws 10, which screws threadedly engage the parts 6 and being provided with heads 11 serve to draw said parts together to grip the edge of the violin. The clip parts 5 and 6 are provided with a bore 12 extending downwardly through the part 5 into the part 6 and a bore 14 extending upwardly through the part 6 into the part 5. The bore 12 is adapted to receive a stem 16 which is fitted with a crank or offset member 17, and pivotally connected to said crank is an oval chin rest 18. The pivot pin 19 of the chin rest 18 is disposed to one side of the major axis of said chin rest, thus permitting the rest 18 to be adjusted to change the point of chin pressure grip on the violin by merely rocking said rest about its pin 19. The bore 14 is fitted with a stem 21 having

2

at its lower end a curved spring arm or shoulder rest 22, which terminates in a cross member 23 pivotally connected thereto by a rivet 24.

In the exemplification shown, the two stems 16 and 21 are arranged in close relation to each other, so that a single thumb screw 26 may be fitted into the back of the part 6 to engage both of said stems and hold them against turning and yet allowing both to be held or released by the manipulation of a single screw only. The inner end of each of the stems 16 and 21 is bored longitudinally and is provided with a small set screw 27 which may be adjusted as to projection from the end of their respective stems, so that the stems can be inserted into their proper position in the bores 12 and 14 with accuracy and with ease.

In use, the shoulder rest 22 will be adjusted to rest upon the shoulder in the most convenient position and the stem 21 will be housed in the bore 14 with its set screw 27 abutting the inner end of the bore. The chin rest 18 will be adjusted as to position and both stems 16 and 21 will be locked by turning the screw 26. It will be obvious that the violin can be supported to suit any player and that when it is desired to put the violin in its case, the chin rest and shoulder rest may be removed subsequent to the slackening of the screw 26. When the violin is again wanted, it suffices to simply replace the chin rest and shoulder rest in the bores 12 and 14 and tighten one screw, when the vertical setting of the violin between chin rest and shoulder support will be exactly as it was before. With the pivotal setting of the chin rest 18 upon its pin 19, a reasonable amount of head movement may take place and slight changes of head and neck position be obtained to the comfort and ease of the player.

40 What I claim as my invention is:

1. A violin support comprising a clip adapted for attachment to a violin, a vertical stem detachably secured in said clip, means for limiting the endwise movement of said stem into the clip, and a chin rest eccentrically mounted and pivotally connected to the stem.

2. A violin support comprising a clip adapted for attachment to a violin, a vertical stem detachably secured in said clip, said stem having a crank at its upper end and a chin rest secured adjacent the outer end of said crank.

3. A violin support comprising a clip adapted for attachment to a violin, a vertical stem detachably secured in said clip, said stem having a crank at its upper end and a chin rest pivot-

ally mounted adjacent the outer end of said crank, said chin rest being eccentrically mounted upon said crank.

4. A violin support comprising a clip adapted for attachment to a violin, said clip having a vertical bore extending downwardly thereinto, a stem adapted for housing in said bore, a chin rest pivotally mounted at the end of said stem, means for limiting the downward movement of the stem into the bore, and means for securing the stem therein.

5. A violin support comprising a clip adapted for attachment to a violin, a chin rest adjustably supported above the clip and a shoulder rest mounted below said clip, said shoulder rest comprising a demountable stem extending downwardly from the clip and having a member secured to said stem adapted to rest upon the shoulder of a player, and unitary means for securing the chin rest and the shoulder rest in adjusted position.

6. A violin support comprising a clip adapted for attachment to a violin, said clip having a pair of vertical bores, one of said bores being closed at the top of the clip and the second of said

15 bores being closed at the base of the clip, a chin rest having a stem inserted in one of the bores and a shoulder rest having a stem inserted in the second of said bores, and means for detachably retaining said stems in said bores.

5 7. In a violin support, a clip having a vertical bore closed at one end, a body contacting member having a stem adapted to be held in said bore, said stem having a screw extension at its inner end, said extension being adapted for adjustment to limit the inward movement of said stem into the bore.
